UNITED STATES PATENT OFFICE.

ARTHUR H. NOBLE, OF PAWTUCKET, RHODE ISLAND, AND RALPH W. WILSON, OF NEW YORK, N. Y., ASSIGNEES TO THEODORE W. FOSTER & BRO. CO., OF PROVIDENCE, RHODE ISLAND.

VANITY CASE.

Application filed January 26, 1926. Serial No. 83,818.

This invention relates to certain new and useful improvements in vanity cases and pertains more especially to a loose powder holder for the case.

5 The primary object of the invention is to provide a powder holder which has novel means for retaining the powder in the holder thereby to prevent the powder from being shaken or otherwise moved out of the holder.

10 A further object of the invention is to provide a powder holder which may be easily and quickly applied to and bodily removed from the case, thereby to enable the holder to be made separately and in various sizes 15 or forms and applied to cases of corresponding size or form.

15 The invention further aims to provide a simple and economical form of powder holder, and has still further and other objects which will be later set forth and manifested in the course of the following descriptions.

20 In the drawings:—

25 Figure 1 is a plan view of a case equipped with the present invention, the case being in open position; and

Figure 2 is a section on line 2—2 of Fig. 1. In proceeding in accordance with the present invention a case is illustrated having a body 1 provided with a rim 2 to which latter a cover 3 equipped with a mirror 4 is hinged at 5 to the rim 2 of the body 1. The rim 2 has a latch, composed of a spring arm 30 6, riveted thereto at 7, the free end of the arm having a catch 8 and the usual finger-engaging ear 9.

40 The powder holder is composed of a body having a bottom 10 provided with a central powder-holding depression or well 11, the bottom 10 affording a ledge which encompasses the well and lies thereabove. A cover 12 is provided for the well and is formed with a shallow central depression 13 45 which is of less diameter than that of the internal diameter of the ledge 10. The cover 12 is hinged at 14 to the ledge 10 and has a spring catch 15 and a finger piece 16, the catch 15 being formed to spring into an opening 17 provided therefor in the top of the body above the ledge. The powder holder further has a depending rim 18 preferably formed to frictionally engage with and within the rim 2 of the body 1.

55 For the purpose of preventing escape of the powder from the well 11, a felt pad or equivalent, 19 is engaged with the cover 12 on the under face of the latter and is secured in place thereon by means of a metal or other disk 20 which engages the felt disk. 60 A rivet 21 is extended through the disks 19 and 20 and the cover depression 13 and serves to clamp the disk 20 against the pad 19 and the latter against the cover 12.

65 The felt pad or disk 19 extends beyond the depression 13 and also beyond the clamping disk 20 so as to permit its peripheral portion 21 to flare into the offset 22 resultant from the depression 13, which portion 21 seats on ledge 10 and provides an effective 70 seal for the well 11, preventing the escape of powder therefrom.

75 The rim 18 of the holder is cutaway at 23 to receive the latching device of the body 1, which latter serves to hold the holder 75 against rotation when applied to the body 1.

80 From the foregoing it will be seen that the holder can be easily and quickly applied to the case without the necessary use of tools or the like and can be removed by merely 85 prying same out by use of any pointed instrument inserted in cutout 23.

Having thus described our invention, what we claim as new and desire to secure by Letters Patent is:—

85 1. In combination with a vanity case having a rim, a powder holder having a body provided with a rim removably engaged in the case rim and having a powder well with a ledge surrounding the latter, a hinged cover for the holder having a central depression forming an offset which latter surrounds the depression, a felt disk-like pad engaged with the under face of depression of the cover and with the offset, and a disk secured 90 to the cover so as to clamp the pad thereto, the pad having a flared peripheral part projecting beyond the clamping disk and seated on the ledge of the holder body.

95 2. In combination with a vanity case having a rim, a powder holder having a body provided with a rim removably engaged in the case rim and having a powder well with a ledge surrounding the latter, a hinged cover for the holder having a central depression forming an offset which latter surrounds the depression, a felt disk-like pad engaged with the under face of depression 100 and within the rim of the body.

105

of the cover and with the offset, and means to secure the pad to the cover so as to allow the peripheral part of the pad to seat on the ledge.

6. 3. In combination with a vanity case, a powder holder having a body formed with a well, a ledge above the top of the well surrounding same and located below the top of the body, a cover for the well hinged to the top of the body, means carried by the cover and seating on the ledge to seal the well, a catch for the cover, a keeper for the catch carried by the top of the body, and a disk secured to the cover for clamping the pad 15 thereagainst, the disk being receivable in the well.

4. In a powder holder, a body having a powder well and a ledge surrounding same, a hinged cover for the body, a pad secured 20 to the under face of the cover and seating on the ledge to seal the well against the escape of powder therefrom and a plate for securing the pad to the cover extending over the central part of the pad and being receivable in 25 the well when the cover is closed.

5. In combination with a vanity case, a powder holder having a body formed with a well, a ledge above the top of the well surrounding same and located below the top of the body, a cover for the well hinged to the top of the body, and having an offset channel, a felt pad on the cover engaged in the channel and seating on the ledge, and a disk secured to the cover for clamping the pad 30 thereagainst and in the channel, the pad extending beyond the disk.

6. In a powder holder, a body, a hinged

cover therefor, a felt pad on the under face of the body, a disk of less diameter than the pad engaged with the under face of the pad, and means to secure the disk and thereby the pad to the cover, the peripheral part of the pad engaging the body so as to prevent the escape of powder therefrom.

7. In combination with a vanity case having an upwardly extending rim, a powder holder having its central part dished to form a powder holding well that is independent of the case, and having its marginal portion extended downwardly to form a depending rim which engages the rim of the body, the part of the top of the body between the well and the rim thereof being offset to form a ledge, a cover for the well, and a pad carried by the cover and seating on the ledge.

8. In combination with a vanity case having an upwardly extending rim, a powder holder having its central part dished to form a powder holding well that is independent of the case, and having its marginal portion extended downwardly to form a depending rim which engages the rim of the body, a pad carried by the cover and seating on the ledge, means to hinge the cover to the top of the body above the ledge, a catch carried by the cover and a keeper for the latch at the top of the body above the ledge.

In testimony whereof I have signed my name to this specification.

ARTHUR H. NOBLE. 70
In testimony whereof I have signed my name to this specification.

RALPH W. WILSON.
